JAMES J. FLANNERY AND ETHAN I. DODDS, OF PITTSBURGH, PENNSYLVANIA, ASSIGNEES TO FLANNERY BOLT COMPANY, OF PITTSBURGH, PENNSYLVANIA.

LAMP STRUCTURE.

1,275,891.

Specification of Letters Patent. Patented Aug. 13, 1918.

Application filed September 13, 1917. Serial No. 191,200.

To all whom it may concern:

Be it known that we, JAMES J. FLANNERY and ETHAN I. DODDS, citizens of the United States, and residing at Pittsburgh, in the county of Allegheny and State of Pennsylvania, have invented certain new and useful Improvements in Lamp Structures; and we do hereby declare the following to be a full, clear, and exact description of the invention, 10 such as will enable others skilled in the art to which it appertains to make and use the same.

This invention relates to improvements in lamp structures and more particularly to 15 such as may be used in places where they are subject to severe shocks,—one object of the invention being to provide a lamp which may be rendered luminous by means of artificial light supplied therein at intervals and 20 for brief periods of time and to so construct such a lamp that it will withstand excessive shocks such as caused by concussion resulting from the firing of guns.

A further object is to provide a lamp of 25 the type specified which may be successfully used on submarines or other war ships without danger of rupture when the guns of the ship are fired.

With these and other objects in view, the 30 invention consists in certain novel features as hereinafter set forth and pointed out in the claims.

In the accompanying drawings; Figures 1, 2 and 3 are views illustrating the method 35 of making the lamp; Fig. 4 is a view showing a completed lamp and Fig. 5 is a view of a slight modification.

1 represents a transparent globe which 40 may be made of glass and the glass may be colored if desired. The wall of the globe is made quite thick so as to be capable of 45 withstanding great shocks without becoming ruptured. Thus the globe 1 may be made from a block of glass suitably shaped 50 to form a bowl-like structure having a flanged upper edge 2, or, if desired the bowl-like heavy globe 1 may be formed without a flange at its edge, and clips 3 employed to take the place of the flange as shown in Fig. 5.

The inner surface of the globe 1 is coated 55 as at 4 with a phosphorescent material which will absorb light,—viz., be activated or energized by artificial light to render it luminous and which will retain its luminos-

ity for a considerable period after the artificial light shall have been extinguished. Such material may comprise zinc or calcium sulfid and a small quantity of radioactive material, such as a salt of radium. 60

The globe 1 after having been coated with illuminating material as above explained, will be partly filled with a transparent plastic material 5, such as glue, gelatin or a thick syrup. An inner globe or tube 6 having one end closed, will then be pressed into the cavity of the outer globe 1, so that the transparent plastic material will constitute a filling between the two globes to prevent such relative vibration as would cause rupture in case of shock, and the surplus plastic material will be forced out when the inner globe is being pressed into position, as illustrated in Fig. 3.

When the inner globe shall have been 75 pressed firmly into the outer globe, its flanged upper edge 7 will overlie the flanged upper edge 2 of said outer globe as shown in Fig. 4 or the clips 3 as shown in Fig. 5.

A source of artificial light is disposed 80 within the inner globe or tube. This may consist of an incandescent electric lamp bulb 8, and the construction should be such as will prevent rupture of the bulb when subjected to shock. This may be accomplished by providing a transparent filling 85 9 between the bulb and the inner globe or tube. Such filling may consist of plastic or glutinous material,—shellac for example. The bulb 8 may be sealed in the globe 90 structure by means of suitable cement as indicated at 10.

Any suitable means may be provided for 95 supplying current to the filament of the incandescent lamp bulb and for controlling the lighting and extinguishing of the same. To activate or energize the illuminating coating, it will be sufficient to maintain a light in the incandescent bulb for a very brief period of time, and to so light the bulb at 100 intervals. The artificial light supplied by the bulb 8 will suffice to so actuate the coating that the latter will remain luminous for a considerable period, and afford sufficient illumination for ordinary purposes where a 105 mild light is desired.

Our improvements are particularly adapted for use in illuminating cabins and other parts of submarines and other war ships where the lamps are subjected to great shock 110

when the ships are in action, and where the economical use of electricity for lighting purposes is an important item.

Having fully described our invention 5 what we claim as new and desire to secure by Letters-Patent, is:—

1. A lamp structure comprising a comparatively heavy globe, an inner globe, a coating of phosphorescent material between 10 said globes, a transparent filling between said globes, and a source of light within the inner globe.

2. A lamp structure comprising a comparatively heavy outer globe having a coating 15 of phosphorescent material on the inner face of said globe, an inner globe, a filling between said globes, and a source of light within the inner globe.

3. A lamp structure comprising an outer 20 globe having a thick wall, an inner globe, a coating of phosphorescent material between said globes, a filling between said globes, an electric lamp within the inner globe and a filling between said electric lamp 25 and the inner globe.

4. A lamp structure comprising an outer globe having a thick wall, an inner globe, a coating of phosphorescent material between 30 said globes, a plastic filling between said 35 globe, and means for sealing said electric lamp within said inner globe.

gloves, an electric lamp within the inner 30 globe, and means for sealing said electric lamp within said inner globe.

5. A lamp structure comprising an outer globe and an inner globe with a coating of phosphorescent material between them, 35 transparent means between said globes for preventing relative movement of the same, and means affording a source of light contained within the inner globe.

6. The herein described method of making 40 a lamp consisting in coating the inner surface of a globe having a thick wall with phosphorescent material, partly filling the globe with a transparent plastic material, forcing an inner globe into the outer globe 45 whereby a transparent filling will be provided between said globes, and securing means providing a source of light within the inner globe.

In testimony whereof, we have signed this 50 specification in the presence of two subscribing witnesses.

JAMES J. FLANNERY.
ETHAN I. DODDS.
